UNITED STATES PATENT OFFICE.

THEODOR EUGEN BUSCHMANN, OF CHEMNITZ, GERMANY, ASSIGNOR TO THE FIRM OF WANDERER WERKE VORM. WINKLHÖFER & JAENICKE AKT.-GES., OF SCHÖNAU, NEAR CHEMNITZ, GERMANY.

TABULATOR FOR TYPE-WRITERS.

1,111,293.

Specification of Letters Patent.

Patented Sept. 22, 1914.

Application filed November 22, 1913. Serial No. 802,575.

To all whom it may concern:

Be it known that I, THEODOR EUGEN BUSCHMANN, a subject of the Emperor of Germany, residing at Chemnitz, Germany, have invented certain new and useful Improvements in Tabulators for Type-Writers, of which the following is a specification.

This invention relates to tabulators for typewriters and is an improvement in or 10 modification of the tabulator mechanism described in the specification of my prior Patent No. 1,035,778, granted August 13, 1912, having for its object a simplification in the adjustment of the tabulator stop bars with 15 relation to the carrying bars for the tabulator stops which correspond to the different headings for invoices required for use. The simplification or improvement in the adjustment consists therein that the adjusting apparatus is so formed that the changing from one position of the tabulator stop bars to another position is performed by turning the parts effecting the adjustment, to the right or to the left.

20 The invention is shown by way of example in the accompanying drawings, in which:—

Figure 1 is a lateral sectional elevation of the frame of the typewriter, and showing 30 the tabulator device constructed according to this invention. Figs. 1^a and 1^b are details. Fig. 2 is a plan according to Fig. 1. Figs. 2^a to 2^c show the adjusting apparatus for the stop bars in different working positions. Fig. 3 is a back elevation. Fig. 3^a is 35 a plan on the guiding member for the stop bar casing. Fig. 4 is a partial elevation corresponding to Fig. 1, but seen from the other side.

40 The paper carriage 1, as described in the specification of the prior patent, above mentioned is guided in the known manner on the front and back carriage bar, and carries at the back thereof the supporting or tabulator bars 2 which are preferably arranged 45 beside each other, for the tabulator stops 3. Stop bars 4 coöperate with these stops 3. The stop bars 4 are inclosed and guided in a casing 6, and are lifted by the tabulator key lever 5 against the action of their tension springs 8, for engagement with the stops 3. All this is substantially described in the specification before referred to.

For the purpose of adjusting the stop

bars 4 relatively to the different carrying 55 bars 2 for the tabulator stops corresponding to the different headings of invoices required, the stop bar casing 6 is connected by means of a link 9 with the pin of a crank disk 10 situated on a shaft 10^a.

The shaft 10^a is mounted in a bearing member 12 secured on the frame of the typewriter and carries at its other end a bevel wheel 11^a, which is in gear with a second bevel wheel 11 mounted on the shaft 14.

The shaft 14 carries at the front of the typewriter, a knob 15 and pointer 16 adapted to move over an indicator scale 17. The crank disk 10 is provided with notches on its circumference with which a clamping 70 ball 13 can engage. The clamping ball 13 is arranged in a holding apparatus on the bearing member 12, and is situated under the influence of a spring, which has a constant tendency to cause the clamping ball 75 to engage with the notches in the crank disk.

The stop bars 4 together with their casing 6, pivot about an axis 7 securely mounted on the frame of the typewriter, and are provided at their lower ends with slotted projections or hooks 18. Pins 19, on the tabulator key levers 5 engage in the slots of said projections. These tabulator key levers rock on a fulcrum pin 25 and are adapted to be operated against the action of tension springs their front ends being guided in the slots of a comb-like rail 20. At the back of the typewriter, another comb-like rail 20^a, Fig. 1^a, is provided, in the rear ends of the slots of 90 which the tabulator key levers 5 are also guided on the other side of the fulcrum pin 25.

The stop bar casing is guided at its upper end in a frame 22, Fig. 3^a, which is preferably placed in a slot in the back carriage bar 95 24 with projecting flaps, and is held by screws 23.

The operation of the device is as follows:— If the stop bars 4 are to be adjusted relatively to the carrying bars 2 for the tabulator 100 stops 3, then the knob 15 is rotated until the pointer 16 on the indicating scale 17 assumes the positions 1, 2, 3 or 4, corresponding to the position desired, after which the tabulator stops 3 are set to begin the work. When 105 moving the knob 15 the crank disk 10 is rotated by means of the shaft 14, the bevel wheels 11, 11^a and the shaft 10^a, and thus by

means of the links 9, the stop bar casing 6 with the stop bar 4 is adjusted. In each position of the crank disk 10 corresponding to the scale, a notch on the circumference of the crank disk is brought opposite the locking ball 13 with which it engages and secures the adjusted position of the parts.

In the Figs. 2^a to 2^d, the various positions of the crank disk 10 and the links 9 are illustrated when using four carrying bars 2 for the tabulator stops. It is to be understood that the notches on the circumference of the crank disk 10 may also be distributed in another manner to that shown, and further that the distribution must correspond with the number of carrying bars for the tabulator stops and with the indicating scale.

As the stop bars 4 cannot effect an efficient guiding on account of their pivotal arrangement, the tabulator key levers 5 as above stated are guided and secured against tilting, by means of the comb-like rail 20, while the stop bar casing is positively guided in the frame 22 so that all parts in action when tables or columns are being typed are securely guided and possess easy movability, whereby rapid and safe working of the tabulators are attained.

I claim—

30 1. In a tabulating device for typewriters, the combination with a plurality of carrying bars, tabulator stops, stop bars, and a casing containing the stop bars; of a crank disk, rotatable means operable to the right or to

the left from the front of the typewriter for 35 rotating said crank disk, a connecting link between the crank disk and casing whereby a predetermined rotational movement of the crank disk adjusts the casing to position the stop bars relatively to the tabulator stops. 40

2. In a tabulating device for typewriters, the combination with a plurality of carrying bars, tabulator stops, stop bars, and a casing containing the stop bars; of a shaft, a notched crank disk at one end thereof, a 45 spring-pressed detent for engaging the notches in the crank disk, a bevel gear wheel on said shaft, an operating shaft, a bevel gear wheel thereon in mesh with the gear wheel on the first mentioned shaft, a knob 50 at the front of the typewriter on the end of the operating shaft for turning the shaft to the right or to the left, a pointer on the operating shaft, an indicator scale for the pointer, and a connecting link between the 55 crank disk and stop bar casing whereby a predetermined rotational movement of the crank disk adjusts the casing to position the stop bars to a predetermined position relatively to the tabulator stops, for the purpose 60 described.

In testimony whereof I have affixed my signature.

THEODOR EUGEN BUSCHMANN.

In the presence of—

E. KILBOURNE FOOTE,
MARTHA ROTHE.
